BUILDING UNIT FOR USE AS PART OF A CLOAKROOM

David Charles Kirby, 28 Warren Way,
Digsowell, Welwyn, England

Filed Dec. 1, 1964, Ser. No. 82,849

Claims priority, application Great Britain June 1, 1964

Term of patent 14 years

(Cl. D4—4)

Fig. 1

Fig. 2

The dominant features of this invention reside in the solid lines of the accompanying drawings.

I claim:

The ornamental design for a building unit for use as part of a cloakroom, substantially as shown and described.
